UNITED STATES PATENT OFFICE.

RICHARD DRAKE, OF RACINE, WISCONSIN, ASSIGNOR TO J. FRED SUGDEN, OF RACINE, WISCONSIN.

DISPENSING DEVICE.

1,224,082.

Specification of Letters Patent. Patented Apr. 24, 1917.

Application filed June 16, 1916. Serial No. 104,043.

To all whom it may concern:

Be it known that I, RICHARD DRAKE, a citizen of the United States, residing at Racine, in the county of Racine and State 5 of Wisconsin, have invented certain new and useful Improvements in Dispensing Devices, of which the following is a specification.

This invention relates to dispensing devices and more particularly to that class of 10 such devices adapted to dispense a predetermined quantity of granular or pulverulent material in order that a desired quantity of the same may be dispensed at the proper time, and has for its primary object 15 the provision of a dispensing device of the character set forth with means for agitating the granular or pulverulent material dispensed thereby so as to insure at all times a proper flow of the material through the device into the receptacle.

A further object of this invention is to provide a device of the character described which shall be adapted to coöperate with the shipping containers for the material to 25 be dispensed and to further coöperate with a stand adapted to support the shipping container in inverted position to dispense the material contained therein.

A further object of this invention is to 30 provide a stirring agitator with a plurality of joints so as to permit of angular movements of the agitator and thus adapt it to reach all parts of the shipping container.

With the foregoing and other objects in 35 view as will from time to time hereinafter appear this invention consists in the peculiar combination and arrangements of the various coöoperating elements of a dispensing device as described in the following 40 specification and more particularly pointed out in the appended claims.

Referring to the accompanying drawings forming a portion of this specification and illustrating the preferred embodiment of the 45 invention and in which the same reference characters indicate the same parts wherever used,

Figure 1 is a perspective view of the device;

50 Fig. 2 is a side elevation of the dispensing head;

Fig. 3 is a section on line 3, 3 of Fig. 2;

Fig. 4 is a bottom view of a dispensing head;

55 Fig. 5 is a detail perspective showing the

parts of the trapping member of the dispensing head in separated relation.

6 designates a suitable base provided with uprights 7 and 8 adapted to support, by means of ears 9 and 10, a dispensing head 11, comprising a hollow cylindrical member 12 having an extension 13 inwardly screw-threaded at 14 to receive the screw-threaded neck 15 of the shipping container 16 for the granular or pulverulent material to be dispensed by the device. The dispensing head 11 is provided interiorly with a central shaft 17 carrying, by means of a pin 18, engaging an extension 19, a ratchet wheel 20 adapted to be rotated by means of a handle 21 provided with a spring-held pawl 23 engaging the teeth of the ratchet wheel 20. This handle is supported about the shaft 17 by means of a collar 24 independent of the shaft 17, and resting upon the upper face 75 of the wheel 20. Suitably keyed to the shaft 17 is a dispensing member 25 comprising a central hub 26 having an extension 27, the said extension 27 extending into the collar 24 but being independent of any movement 80 thereof. The hub 26 is provided with a plurality of radial extensions 27' extending to the interior periphery of the dispensing head for a purpose hereinafter set forth. Directly above the member 25 is a segment 85 shaped plate 28 provided with a central aperture 29 adapted to receive the shaft 17 but not to coat therewith, and a fan-shaped extension 30 provided with a small aperture 31 adapted to engage a projecting pin 32 90 upon the lower face of the flange member 12 to prevent rotation of the member 28 with the shaft 17.

Directly below the fan-shaped portion 30 of the member 28 is an aperture 33 formed 95 in the base 34 of the dispensing head 11 and having communicating therewith a discharge spout 35 suitably secured to the base of the member 11. The shaft 17 passes upwardly through the center of the cylindrical member 13 where it is provided with a knuckle joint 36 which carries a short extension 37 provided with a second oppositely disposed knuckle joint 38 adapted to permit of movement of the shafting connected therewith in an opposite direction to that of the movement permitted by the knuckle joint 36. From the knuckle joint 38 extends a shaft 39 provided with a plurality of agitating stirrers 40 which extend 110

at angles to the shaft into the granular material within the container 16, one of the stirrers being bent at 40' to form an agitator adapted to clean the neck of the container 16. The shaft 17 is also provided with a plurality of stirrers 40^a to agitate the material within the throat of the member 12.

The operation of the device is as follows:

The device is placed in position upon a counter or soda-fountain or the like with the shipping container for the granular material placed in inverted position as shown, within the threaded flange 13, the shaft 39 extending upwardly into the vessel, whereupon the granular material from the container 16 will flow downwardly through the throat of the member 13 into the chambers formed between the extensions 27 of the member 25, the further flow of the material being stopped by the base 34 of the dispensing head 11 and any flow of material through the spout 35 being normally prevented by the closure of such spout by the fan-shaped portion 30 of the member 28. When it is desired to dispense a predetermined amount of the granular material a suitable receptacle, such as a glass or tumbler, is placed beneath the spout 35 and the handle 21 moved to cause the ratchet wheel 20 to be rotated through a certain distance, in order to cause the member 25 and its corresponding extensions 27' to move the same distance, thus bringing one of the chambers formed between the members 27' over the opening 33, whereupon the granular material contained in such chamber will fall through the opening 33 into the spout 35 and into the receptacle into which it is desired to dispense this amount. Should it be desired to dispense only one portion of the granular material the handle is moved into the position shown in central dotted position in Fig. 4, and then moved to the position shown in full lines in the said figure, which will cause only one of the chambers formed by the members 27' to deposit its granular material into the spout 35. Should it be desired however to dispense a double quantity into the same receptacle the handle is moved to the position shown in dotted lines at the top of Fig. 4, that is to say past two cogs of the ratchet wheel 20, and then carried forward into the position shown in full lines in Fig. 4, thus causing two chambers formed by the members 27' to pass over the opening 33 and discharge their contents therethrough. During the dispensing operation the shaft 17 has caused the shaft 39, through the medium of the knuckle joints 36 and 38 and the intermediate shaft 37 to rotate within the container 16 and to agitate the granular material contained therein, the knuckle joints 36 and 38 causing a deviation from a straight line movement of the shaft 39, thus causing the agitating stirrers 40 to

reach every point within the receptacle 16 and effectually agitate and stir the granular or pulverulent material contained therein to such a degree that all lumps or undesirable thicknesses of the material are broken up effectively, thus preventing the clogging of such material and effecting a free flow thereof.

As many changes could be made in the above construction and many apparently widely different embodiments of my invention could be made, without departing from the scope thereof, it is intended that all matter contained in the above description or shown in the accompanying drawings shall be interpreted as illustrative and not in a limiting sense.

What I claim as new and desire to secure by Letters Patent is:

1. A dispensing device comprising a stand, a dispensing head removably mounted thereon, means carried by said head for removably supporting a container, a spout from said head, a dispensing member in said head, said dispensing member comprising a body portion provided with a plurality of radial extensions, and a depending extension, a shaft passing through said dispensing member, a ratchet on said shaft, a plurality of agitating members on said shaft adapted to stir the granular material in the container, means for rotating the shaft and means for permitting an angular movement of said shaft in addition to said rotation.

2. A dispensing device comprising a stand, a dispensing head removably mounted thereon, removable means carried by said head for removably supporting a container, a dispensing member in said head, means carried by the dispensing member adapted to agitate the material within the container, and means for permitting an angular movement of said agitating means.

3. A dispensing device comprising a stand, a dispensing head thereon, a dispensing member in said head, said member consisting of a body portion having a plurality of radial extensions and a depending extension, a shaft passing through said body portion and adapted to turn therewith, a ratchet on said shaft, a handle rotatably journaled on said extension, a pawl on said handle in engagement with the ratchet, whereby movement of the handle will rotate said shaft and the dispensing member.

4. A dispensing device comprising a head adapted to support a container, a dispensing means carried by the head, means for operating said dispensing means, and agitating means capable of rotary and angular movement adapted to operate in conjunction with the dispensing means.

5. A dispensing device comprising a head adapted to support a container, dispensing means in said head, a shaft extending from

said dispensing means into the container, a plurality of knuckle joints on the shaft, and means for rotating the shaft.

6. A dispensing device comprising a head adapted to support a container, dispensing means in said head, a shaft extending from said dispensing means into the container, a plurality of knuckle joints on the shaft, a plurality of agitating means on said shaft,

some of said agitating means being formed to correspond to the contour of said container, and means for rotating the shaft.

In testimony whereof I affix my signature in the presence of two witnesses.

RICHARD DRAKE.
